(57) **CLAIM**

The ornamental design for a vacuum pump, as shown and described.

DESCRIPTION

FIG. 1 is a perspective view from the top front left side;

FIG. 2 is a rear view;

FIG. 3 is a front view;

FIG. 4 is a top view;

FIG. 5 is a bottom view;

FIG. 6 is a view from the left side; and,

FIG. 7 is a view from the right side.

The broken lines are included for the purpose of illustrating a portion of the vacuum pump that forms no part of the claimed design.
